ATTORNEY

UNITED STATES PATENT OFFICE.

GEORGE ISAAC SHELTON, OF FORT WORTH, TEXAS, ASSIGNOR OF ONE-HALF TO ROY GINN, OF FORT WORTH, TEXAS.

TELEGRAPH INSTRUMENT.

Application filed May 31, 1921. Serial No. 473,681.

To all whom it may concern:

Be it known that I, GEORGE I. SHELTON, a citizen of the United States, residing at Fort Worth, in the county of Tarrant and 5 State of Texas, have invented new and useful Improvements in Telegraph Instruments, of which the following is a specification.

This invention relates to a telegraph instrument, and the object is to provide an improved form of contact for a sending device 10 of the so-called "autodot type."

A serious difficulty in the type of instruments named is due to the fact that the resiliently mounted contact is disposed at a 15 slight angle with reference to the stationary contact element, so that the circuit is not properly completed, and when atmospheric conditions are bad, or when dust collects on the contacts, it is impossible to use the instrument with success. This slight angle 20 is apparent when the resilient contact yields to the pressure of the pendulum.

One of the chief objects of the present invention is therefore to provide a pair of contact elements each acting under the influence 25 of a spring and maintaining approximate alinement under all conditions, with the result that a reliable contact is made and the circuit is properly completed, or broken as 30 the case may be, a split dot being an impossibility.

With the foregoing and other objects in view, the invention consists in the novel construction, combination and arrangement 35 of elements described and claimed, it being understood that modifications may be made within the scope of the claims, without departing from the spirit of the invention.

In the drawings—Figure 1 is a top plan 40 view of the instrument, and Figure 2 is a detail view showing the resiliently mounted contacts, in alinement, and the adjusting means.

Several of the elements of the instrument may be of standard construction, and referring to the drawings in detail, the base is 45 designated 10, a vertical frame being shown at 12, and the arms 13 and 14 carry adjusting screws 15 and 16.

Finger pieces 18 and 19 are carried by the 50 element 20. The pendulum is designated 21, and a spring 22 controlled by adjusting the screw 23 serves the usual purpose. The circuit is completed at 24 when sending the dash.

Carried by the element 21 is a collar 25 retained by a set screw 26, and this collar is provided with a radial bore 27 in which the spring contact 28 is mounted.

A cooperating contact 30 is in alinement 60 with the contact element 28, and is mounted in a bore 31 of adjusting screw 32, being connected with the main line.

Hence these contacts maintain approximate alinement during operation, and the 65 circuit will be fully completed, or sharply broken, and difficulties arising from a weak current, due to imperfect contact will be wholly avoided.

Practical tests by experienced operators 70 have fully demonstrated the utility and effectiveness of the device.

Having described the invention what is claimed is:—

In a telegraph device of the class described, a plurality of adjustable elements 75 each provided with a bore, a contact pin mounted in each bore, a spring within each bore serving to control the movement of the pins mounted therein, said pins being movable in the direction of their longitudinal axes and maintaining alinement with each other.

In testimony whereof I affix my signature.

GEORGE ISAAC SHELTON.
